UNITED STATES PATENT OFFICE

171,284

HOLDER FOR WAX APPLICATOR OR THE LIKE

Alfred L. Le Febvre, Windsor, Conn., and Douglas M. Small, Springfield, Mass., assignors to Stanley Home Products, Inc., Westfield, Mass., a corporation of Massachusetts

Application May 28, 1953, Serial No. 25,219

Term of patent 14 years

(Cl. D9—2)

To all whom it may concern:

Be it known that, we, Alfred L. Le Febvre and Douglas M. Small, both citizens of the United States, residing at Windsor, Connecticut, and Springfield, Massachusetts, respectively, have invented a new, original, and ornamental Design for Holder for Wax Applicator or the like, of which the following is a specification, reference being had to the accompanying drawings, forming part hereof:

Fig. 1 is a top plan view of a holder for wax applicator or the like, showing our new design;

Figs. 2, 3 and 4 are cross sectional views on the lines 2—2, 3—3, and 4—4, respectively, on Fig. 1.

We claim:

The ornamental design for a holder for wax applicator or the like, as shown.

ALFRED L. LE FEBVRE.
DOUGLAS M. SMALL.
